UNITED STATES PATENT OFFICE

167,589

MINIATURE TRAIN

Joseph P. Ruth, Denver, Colo.

Application November 22, 1950, Serial No. 13,089

Term of patent 14 years

(Cl. D66—1)

To all whom it may concern:

Be it known that I, Joseph P. Ruth, a citizen of the United States of America, residing at the city and county of Denver, State of Colorado, have invented a new, original, and ornamental Design for a Miniature Train, of which the following is a specification, reference being had to the accompanying drawing, forming part hereof.

Figure 1 is a side elevation of a miniature train, showing my new design, an intermediate portion of the view being broken away to conserve space. Figure 2 is an elevation of the opposite side of the train shown in Figure 1. Figure 3 is a front end elevation of the train shown in the preceding views. Figure 4 is a rear end elevation of the train represented by the other views of the drawing.

Figure 5 is a side elevation, on a relatively reduced scale, of the complete articulated trail unit embodying the new design.

I claim:

The ornamental design for a miniature train, as shown.

JOSEPH P. RUTH.
